Primary Examiner — Andrew Kerr*Assistant Examiner* — Courtney J Clark-Rasheed(57) **CLAIM**

The ornamental design for a basketball-shaped cup, as shown and described.

DESCRIPTION

FIG. 1 is a perspective view of a basketball-shaped cup showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is an exploded view thereof; and,

FIG. 9 is an exploded view of the basketball-shaped cup indicating a structure of the cup when the cover is opened. The broken lines indicate disclaimed portions and form no part of the claimed design.
